UNITED STATES PATENT OFFICE

151,322

DESIGN FOR A DOUGH EXTRUSION DEVICE
OR LIKE ARTICLE

Salvatore Cenci, Kansas City, Mo.

Application July 24, 1947, Serial No. 140,482

Term of patent 14 years

(Cl. D44—29)

To all whom it may concern:

Be it known that I, Salvatore Cenci, a citizen of the United States, residing at Kansas City, in the county of Jackson and State of Missouri, have invented a new, original, and ornamental Design for a Dough Extrusion Device or Like Article, of which the following is the specification, reference being had to the accompanying drawing, forming part thereof.

Fig. 1 is a perspective view of a dough extrusion device, showing my new design.

Fig. 2 is a plan view thereof.

Fig. 3 is a front elevational view thereof.

Fig. 4 is a side elevational view thereof.

I claim:
The ornamental design for a dough extrusion device or like article, substantially as shown.
SALVATORE CENCI.
